UNITED STATES PATENT OFFICE.

OTTO A. LEHMAN, OF HOBOKEN, NEW JERSEY.

DESIGN FOR A SHOPPING-BAG.

SPECIFICATION forming part of Design No. 24,849, dated November 5, 1895.

Application filed April 16, 1894. Serial No. 507,770. Term of patent 14 years.

To all whom it may concern:

Be it known that I, OTTO A. LEHMAN, of Hoboken, in the county of Hudson and State of New Jersey, have invented and produced a new and original Design for Ladies' Shopping-Bags, of which the following is a specification, reference being had to the accompanying drawings, forming a part thereof.

The essential feature of my design consists in a lady's shopping-bag, presenting a low-cut border across the bottom and up the ends of the sides of the bag contrasting with the material which fills the space between the top, bottom, and ends of the side.

Figure 1 represents the bag in side eleva-

tion, and Fig. 2 represents a central cross-section through the line $x-x$ of Fig. 1.

The ends of the low-cut border or yoke are represented by A, the bottom by A', and the filling of contrasting material between the bottom and ends of the yoke and the top of the bag is denoted by B. The edge of the low-cut border is represented as scalloped.

What I claim is—

The design for a bag, substantially as herein shown and described.

OTTO A. LEHMAN.
